UNITED STATES PATENT OFFICE.

HARRY A. HOKE, OF ALTOONA, PENNSYLVANIA.

LOCOMOTIVE-BRAKE.

1,272,044.

Specification of Letters Patent.

Patented July 9, 1918.

Application filed March 14, 1918. Serial No. 222,284.

To all whom it may concern:

Be it known that I, HARRY A. HOKE, a citizen of the United States of America, residing in Altoona, in the county of Blair, 5 in the State of Pennsylvania, have invented certain new and useful Improvements in Locomotive-Brakes, of which the following is a true and exact description, reference being had to the accompanying drawings, 10 which form a part thereof.

My present invention relates to locomotive brakes, and particularly to the arrangement of the brake cylinders and the rigging by which the motion of the brake cylinder 15 pistons is transmitted to the brake shoes. In the past it has been the practice to employ two brake cylinders, arranged side by side to actuate the driver brakes on certain classes of locomotives, but with the heavy 20 type of locomotives now in use it is impossible, on account of the size of the brake cylinders and frame strength considerations to mount the two brake cylinders side by side. To overcome these difficulties I have 25 heretofore devised an arrangement for which Letters Patent No. 1,099,922 were granted me June 16th, 1914, in which two cylinders are arranged one with its axis vertical and the other with its axis horizontal. This 30 arrangement, while proving generally satisfactory in extensive use, is open to the objection that the horizontally disposed cylinder and piston parts wear more rapidly than do the vertical cylinder and piston parts.

The general object of the present invention is to avoid the above mentioned difficulties by providing a simple and effective arrangement in which a plurality of brake cylinders may all be vertically disposed on 40 a locomotive with their axes in, or closely adjacent to the central longitudinal vertical plane of the locomotive. The novel features of construction and arrangement which characterize my invention are pointed out 45 with particularity in the claims annexed, to and forming a part of this specification. For a better understanding of the invention, however, and the advantages possessed by it, reference should be had to the accompanying drawings and descriptive matter in 50 which I have illustrated and described a preferred embodiment of my invention.

Of the drawings:

Figure 1 is a somewhat diagrammatic plan 55 of the front section of the so-called Mallet

or articulated type of locomotive, which is equipped with my improvement.

Fig. 2 is a somewhat diagrammatic elevation of the locomotive section shown in Fig. 1.

Fig. 3 is a somewhat diagrammatic plan of the rear section of the locomotive shown in part in Figs. 1 and 2.

Fig. 4 is a somewhat diagrammatic elevation of the locomotive section shown in Fig. 3.

Fig. 5 is a section taken on the line 5—5 of Fig. 3 with parts broken away and removed.

Fig. 5^A is a section on the line 5^A—5^A of Fig. 3.

Fig. 6 is a partial front end elevation of the locomotive section shown in Figs. 1 and 2, with the side frames in section.

While the invention is not limited to use 75 in a locomotive of the Mallet type, it is of especial value when so used, and I have accordingly illustrated its use in connection with such a locomotive. The front section of the locomotive shown in Figs. 1 and 2 80 comprises the usual side frames A and driver elements B', B², B³ and B⁴, each consisting of a pair of driver wheels and their common axle. The drivers are mounted in the side locomotive frames in the usual manner, details of the mounting being omitted from the drawings. The brakes for the drivers B' and B² are operated by the brake cylinder C', which is secured midway between the side frames A A with its axis vertical, and 85 with its piston stem C⁵ projecting through the lower end of the cylinder and link connected to the long arms of two bell crank or rocker levers D', which turn about the axis of a shaft E, having its ends mounted 90 in the side frames. The long arms of the bell crank or rocker levers D' are bent or offset to permit their free ends to approach the longitudinal vertical plane of the locomotive in which the axis of the cylinder C is 95 located, while allowing the hub portions D⁷ of the levers to be spread apart so that each is located adjacent the corresponding side frame A. This reduces the diameter which it is necessary to give the shaft E in order 100 to secure the desired strength and stiffness. The short arm D⁸ of each lever D' is connected by a crank pin D⁹ to the front end of the corresponding pull rod or link F'. Each link F' is pivotally connected at its 105

110

rear end to the middle portion of a corresponding short equalizing bar G' lying a short distance in front of the brake beam I' for the front pair of drivers B' . The outer 5 ends of the two equalizing bars G' are connected by a corresponding pair of links H to the brake beam I' . The inner ends of the equalizing bars G are connected by links L to the opposite ends of a short equalizing bar 10 M located back of the brake beam I' . The center of the equalizing bar M is connected by a link N to the center of the brake beam I^2 for the second pair of drivers B^2 . The 15 brake heads J are pivotally suspended from the side frames, and the brake rigging thereby supported, by means of swinging links K' and K^2 .

It will be apparent to those skilled in the art that the means for operating the brake 20 beams I' and I^2 are simple, effectively disposed, and insure a proper equalization of the braking pressure applied to the different driver wheels B' and B^2 .

The brake rigging for the drivers B^3 and 25 B^4 is essentially identical with that for the drivers B' and B^2 , and comprises parts C^2 , D^2 , E , F^2 , G , H , I^3 , I^4 , J , K^3 and K^4 , corresponding exactly with the parts C' , D' , E , F' , G , H , I , L , M , N , I' , I^2 , J , K^4 and K^5 , 30 except that for structural reasons the shape and proportions of some parts have been changed slightly, and that it is convenient to arrange the axis of the brake cylinder C^2 with its axis very slightly inclined to the 35 vertical.

The rear section of the locomotives shown in Figs. 3 and 4 comprises side frames A' and pairs of drivers B^5 , B^6 , B^7 , and B^8 mounted therein. The brake beams I^6 and I^8 40 for the drivers B^5 and B^6 are operated by a vertically disposed cylinder C^3 , and the brake beams I^7 and I^8 are operated by a cylinder C^4 , by intervening brake rigging practically identical with that through 45 which cylinders C' and C^2 operate the brake beams I' and I^2 , and I^3 and I^4 respectively, except in the respects noted in the following paragraph.

On account of the location of the fire box 50 (not shown) on the rear section of the locomotive, it is practically desirable to locate the brake cylinder C^4 in front of instead of the rear of the drivers B^7 . This involves an elongation of the links or connecting rods 55 connecting the short arms of the bell crank levers D^4 to the short equalizing bars G immediately in front of and connected to the brake beam I' , and the division of each of these rods into two sections F^4 and F^{40} , 60 which are pivotally connected together at their adjacent ends and are supported at their point of connection from the locomotive frame by a corresponding swinging link K^6 . The location of the brake cylinder 65 C^4 in front of the drivers D^7 also makes it

necessary to change the linkage connecting the brake beams I^5 and I^6 to the cylinder C^3 from that employed to connect the brake beams I' and I^2 to the cylinder C' . This change involves connecting the links H^6 to 70 the inner ends of the equalizing bars G , in front of the brake beam I^6 , and connecting the outer ends of these equalizing bars G by links L^6 elongated for the purpose to the opposite ends of an equalizing bar M^6 , 75 which is pivotally connected directly to the brake beam I^6 . As shown, the equalizing bar M^6 is formed of two similar parts mounted one above and one below the brake beam I^6 , and pivotally connected thereto by 80 a stud or pivot pin O passing through the beam I^6 . The ends of the two parts of the equalizing bar M^6 are connected together by posts O^6 , which pass through openings I^{10} formed for the purpose in the brake beam 85 I^6 . These openings are elongated sufficiently to permit all necessary relative angular movement of the brake beam I^6 and the compound equalizing bar M^6 . In effect my invention in its broader aspects consists in 90 providing a separate brake mechanism consisting of a vertically disposed cylinder and suitable equalizing connections for the two brake beams of each of a plurality of pairs of driver elements. By doing this, I am 95 enabled to obtain ample braking power with a single and effective transmission to the driver wheels of a heavy locomotive in which the space available for the disposition of the brake actuating mechanism is 100 much restricted.

While in accordance with the provisions of the statutes I have illustrated and described the best embodiments of my invention now known to me, it will be apparent to those skilled in the art that changes may be made in the form, proportion and relative arrangement of parts without departing from the spirit of the invention as set forth in the appended claims, and that 105 certain features of the invention may sometimes be used with advantage without a corresponding use of other features.

Having now described my invention, what I claim as new and desire to secure by 115 Letters Patent, is:

1. In a locomotive the combination with the frame and a plurality of pairs of drivers, of a brake mechanism for applying a braking force to two of said pairs of drivers, comprising a vertically disposed brake cylinder, a brake lever shaft having its ends mounted in the side frames, a pair of bell crank levers mounted on said shaft, and having their hub portions adjacent the side frames, and each having an arm bent or offset to bring its free end into proximity to the axis of the brake cylinder piston and connected to the latter, a pair of brake beams, one for each of said two pairs of 120 125 130

- drivers and equalizing connections between said brake beams and rock levers.
2. In a locomotive, the combination with the locomotive's side frames and a plurality of pairs of driver elements, of a separate brake mechanism for each pair of driver elements comprising a centrally disposed vertical brake cylinder, a transverse brake lever shaft having its ends mounted in the side frames, a pair of bell crank levers mounted on said shaft, and having their hub portion adjacent the side frames, and each having an arm bent or offset to bring its free end into proximity to the axis of the brake cylinder piston and connected to the latter, a pair of brake beams, one for each driver element, and equalizing connections between each of said brake beams and the other arms of said levers.
3. In a locomotive, the combination with the locomotive side frames and a pair of driver elements, of a brake mechanism for applying a braking force to said pair of driving elements comprising a centrally disposed vertical brake cylinder, a brake lever shaft having its ends mounted in the side frames, a pair of bell crank levers mounted on said shaft, and having their hub portions adjacent the side frames, and having arms bent or offset to bring their free ends in proximity to the axis of the brake cylinder piston and connected to the latter, pull rods connected to the second arms of the bell crank levers, a pair of equalizing bars pivotally connected between their ends one to each of said pull rods, a brake beam for one of said driver elements to which one end of each of said equalizing bars is link connected, links connecting the opposite ends of the equalizing bar to a third equalizing bar, and a brake beam for the second driver element pivotally connected to the last mentioned equalizing bar.
4. In a locomotive, the combination with the locomotive side frames and a pair of driver elements, of a brake mechanism for applying a braking force to said pairs of driver elements, comprising a centrally disposed vertical brake cylinder, a brake lever shaft having its ends mounted in said side frames, a pair of bell crank levers mounted on said shaft, and having their hub portions adjacent the side frames, and each having a long arm bent or offset to bring its free end into proximity to the axis of the brake cylinder piston and connected to the latter, a pull rod connected to the other arm of each bell crank lever, a pair of equalizing bars pivotally connected between their ends one to each of said pull rods, a brake beam for one of said driver elements to which one end of each of said equalizing bars is link connected, links connecting the opposite ends of the equalizing bar to a third equalizing bar, and a brake beam for the second driver element pivotally connected at its center to the center of the last mentioned equalizing bar, the latter being formed of two parts, one located above and one located below the brake beam to which it is pivotally connected, and being connected to the latter by a stud or pivot pin passing through the beam and the two parts of the equalizing bar, said beam being transversely slotted adjacent the ends of the equalizing bar parts, and posts connecting the ends of the two equalizing bar parts passing through said slots.
